FLOTATION MACHINE

Alva H. Garrett, Denver, Colo., assignor of fifty
per cent to Charles O. Parker, Denver, Colo.

Application February 15, 1938, Serial No. 190,594

9 Claims. (Cl. 261—93)

This invention relates to a flotation machine and has for its principal object the provision of a highly efficient device of this character which will have a maximum capacity in proportion to its size; in which the impeller shaft will be supported in two widely spaced-apart bearings, one of which will be adjacent the impeller, so that a relatively small shaft and a comparatively high speed may be used; and in which the bearing 5 adjacent the impeller will be completely protected from sand and solution even though it be located well below the solution level in the machine.

Other objects of the invention are to provide 15 a bottom feed type of cell of large capacity, in which the impeller will rotate in a clear zone free from sand; and to provide a machine in which an exceedingly intimate and efficient mixture of air and pulp is obtained; and in which a very 20 rapid and continuous flow through each cell is possible without decreasing the flotation efficiency.

Other objects and advantages reside in the 25 detail construction of the invention, which is designed for simplicity, economy, and efficiency. These will become more apparent from the following description.

In the following detailed description of the invention reference is had to the accompanying 30 drawings which form a part hereof. Like numerals refer to like parts in all views of the drawings and throughout the description.

In the drawings:

Fig. 1 is a side elevation of a series of cells in 35 which the invention is embodied. This view partially is broken away to show the interior construction.

Fig. 2 is a plan view thereof.

Fig. 3 is a longitudinal section taken on the 40 line 3—3, Fig. 2.

Fig. 4 is a detail plan view of the impeller employed in this invention.

Fig. 5 is a cross-section through the impeller taken on the line 5—5, Fig. 4.

Fig. 6 is a detail cross section through one of the cells taken on the line 6—6, Fig. 2.

The machine consists of a series of aligned cells, each cell being the duplicate of the adjacent cells, all being supported upon any suitable 50 framework such as indicated at 10. Each cell consists of a lower cylindrical bowl 11 terminating at its bottom in an axially positioned, depressed impeller housing 12. The impeller housing is preferably inverted cone-shaped and 55 closes a similarly shaped impeller 13.

The impeller 13 is carried on the lower extremity of a vertical drive shaft 14 which extends downward through the bowl 11. The shaft 14 is mounted in an upper bearing 15 and a lower bearing 16 both of which are mounted in a stationary bearing tube 17 which is secured to and suspended from suitable cross beams 18 positioned transversely of the frame work 10.

Water from the cell is prevented from entering the bearing tube 17 by means of a cylindrical 10 cup member 19 which is secured to and sealed to the shaft 14 below the lower bearing 16 and which extends upwardly about the tube 17 to a point above the solution line in the cell. The cup member 19 rotates as a unit with the shaft 15 14 and is preferably entirely supported thereby.

An air jacket 20 surrounds the cup member 19 and extends from a point above the solution line, downwardly into the bowl 11. The air jacket is preferably tapered and sets by gravity 20 in supporting bracket ring 21. The air jacket is reduced in size below the cup member 19 and is open at its bottom immediately above the impeller 13.

The bottom of the impeller housing 12 is flanged 25 inwardly as shown at 22 to a central opening 23 immediately below the impeller 13.

The impeller 13 consists of a conical outer sleeve or rim which is supported relatively close to, and in parallel relation with, the inner wall 30 of the impeller housing 12. It does not contact the latter, however. The rim is supported from a cup-like hub member 24 by means of radial vanes 25 which extend the full length of the rim. The hub member 24 extends upwardly above the 35 rim and, when in place in the machine, extends within the reduced, lower extremity of the air jacket 20. The hub member is formed with air ports 26 in its side wall and with ports 27 in its bottom.

The pulp and solution to be treated is fed into 40 the impeller housing by means of a bottom feed pipe 28 which extends throughout the entire series of cells between the impeller housings.

The bowl 11 terminates at its top in a rectangular box portion 29, the floor of which is indicated at 30. The bowl passes and is sealed to the floor 30. At each side of the box portion 29 is a deflecting plate 31 extending the full length of the cell. The plates 31 outline the 45 upper portion of the cell and the bowl 11 forms the lower portion thereof.

The sides of the box portion 29 extend downwardly at each side of the deflecting plates 31 and terminate above the floor 30, the interven- 55

ing space being filled with baffle grid 32 at each side of the cell. The top of the box portion 29 is closed by means of a cover 33, through which the air jacket 20 extends and is sealed by means 5 of suitable packing 34. Thus, a compression zone 35 is formed at the top of each cell by the completely enclosed box portion.

Along each side of each cell below the grids 32 is a pulp launder 36 and along each pulp 10 launder is a froth launder 37.

It is desired to call attention to the fact that the entire impeller assembly and air jacket can be lifted from the cell without discharging the contents thereof, by simply lifting the cross members 18 from the frame work. The assembly 15 can also be raised or lowered to adjust the clearance of the impeller by simply raising the cross members 18 or the bearing tube 17 by means of suitable spacing shims or other means. The 20 air jacket can also be raised or lowered by adjusting the wedge-shaped sealing jacket 34 in the cover 33 to obtain the proper clearance between the bottom of the jacket and the impeller.

Should additional air be desirable in the cells, 25 this may be obtained from a compressed air line 49 which communicates with each impeller housing through an air inlet nipple 50 controlled by means of an air valve 51. This air enters the housing in the narrow evacuated space around 30 the impeller and discharges directly into the bowl of the cell in a thin conical sheet which interferes in no way with the vacuum of the impeller.

The flow along the feed pipe 28 is controlled 35 by means of suitable gate valves 46. These valves are normally closed during operation of the machine and are only used for cutting out a certain cell of the series for repairs, etc., by by-passing the pulp from the preceding cell to 40 the succeeding cell through the impeller housing of the intervening cell, or for washing out the entire battery of cells.

The shafts 14 may be driven in any desired 45 manner. It is preferred however, to mount individual drive motors on each set of the cross members 18 connected directly to flanges 52 on the shafts. This allows the motor to be lifted as a part of the impeller assembly when removing or adjusting the latter.

50

Operation

The pulp is fed into the first cell of the series through the feed pipe 28. The impellers in all 55 cells are rotating in the housing 12 due to the centrifugal action of the impeller which draws the pulp upwardly through the central opening 23 into the hollow impeller from whence it is discharged upwardly and outwardly into the bowl. This upward and outward centrifugal action 60 completely evacuates the space between the impeller and the impeller housing wall so that there is no friction or wear at this point.

The out-going pulp creates a partial vacuum 65 immediately below the hub portion 24 of the impeller which draws in additional pulp and also creates a partial vacuum below the air jacket 20 which draws air downwardly in this jacket and through the open bottom thereof. The larger portion of this air enters the hollow hub 70 of this air jacket through the ports 26. Another portion passes downwardly through the ports 27 into the rapidly moving pulp. Still another portion is drawn outwardly between the hub 24 and the open bottom of the jacket.

75 This causes a very intimate emulsification or

intermixing of the air and pulp and creates a pulp pressure within the bowl which forces the pulp upwardly between the plates 31 and against the top of the cell 33 from whence it falls downwardly through the grills 32 into the pulp launders 36.

The solution level in the launders is maintained substantially at the over-flow lip to the froth launders 37 by means of a suitable discharge valves to be later described. The froth flows across the surface of the pulp in the pulp launders into the froth launders 37. The bottoms of the pulp launders are inclined downwardly toward the discharge end of the cells, as shown in Fig. 1, and the pulp flows down this incline to the lowermost point at each side from whence it flows into inwardly extending pulp passages 39 to a pulp chamber 40. From the chamber 40 the pulp flows beneath a floor 41, of a feed chamber 42, thence upwardly to the latter. The flow from the pulp chamber into the feed chamber 42 is controlled by means of an adjustable plug valve, which will be herein designated the discharge valve 43. From the feed chamber 42 the pulp flows through a feed valve 44 to the feed pipe 28 of the next cell.

Each pulp chamber 40 is provided with a bypass valve 45 which can be used to allow a portion of the pulp to by-pass to the feed pipe 28 thence back to the impeller housing of the cell 30 from which it has just been discharged.

Each cell carries its own feed chamber 42 and a discharge chamber 40 which project from that cell into a receiving depression in the adjacent cell so that the entire series of cells interlock 35 one with another. The chambers 40 and 42 are separated by means of an adjustable height partition 47, over which the pulp may flow in case of surges or valve stoppages into the feed chamber 42 of the next cell. Ordinarily, however, 40 the discharge valves 40 are so adjusted as to maintain the proper solution height in each cell so that there is no overflowing at this point.

The valves 43, 44, and 45, are controlled from the top of the cell by means of suitable valve 45 handles 43', 44', and 45', respectively. The air can enter the jacket 20 through the open top thereof there being air holes 48 to facilitate its entrance. The cells may be drained by means of suitable drain cocks 53.

The bearing tube 17 and the interior of the cup member 19 are always free from pulp and solution. The intervening space between the cup member 19 and the air jacket 20 is immediately evacuated by the impeller so that the cup member 19 rotates freely in air without solution friction.

It will be noted that this invention produces a light-weight, fast-moving machine which greatly reduces transportation and installation costs. It 60 passes a small volume of pulp continuously at a rapid rate thereby greatly reducing the time element over the slow-motion, large-volume machines. This results in a low power and maintenance cost and in view of the fact that the 65 entire impeller assembly can be quickly and easily removed, there is a minimum loss of time for repairs or replacements.

The machine incorporates: a gravity flow feed; delivery of the pulp to a quiet froth zone 70 which receives all of the pulp flow; a positive control of pulp level; and returns a volume of pulp to the agitating chamber which gives a positive control of the gravity flow from cell to cell.

While a specific form of the improvement has been described and illustrated herein, it is desired to be understood that the same may be varied, within the scope of the appended claims, 5 without departing from the spirit of the invention.

Having thus described the invention, what is claimed and desired secured by Letters Patent is:

1. In a flotation cell, means for supporting an

10 impeller adjacent the bottom of said cell, comprising: a vertical shaft extending downwardly within said cell to said impeller; a shaft support extending downwardly adjacent said shaft; means supporting said shaft at its upper extremity; bearings carried by said shaft support and supporting said shaft in said cell, the lowermost bearing being positioned adjacent said impeller; and a tubular cup member sealed to said shaft below said lower-most bearing and extending 15 upwardly concentrically thereabout to enclose said shaft support and to prevent said solution from reaching said bearings.

2. In a flotation cell, means for supporting an impeller adjacent the bottom of said cell, comprising: a vertical shaft extending downwardly within said cell to said impeller; a shaft support extending downwardly adjacent said shaft; means supporting said shaft at its upper extremity; bearings carried by said shaft support 20 and supporting said shaft in said cell, the lowermost bearing being positioned adjacent said impeller; a tubular cup member sealed to said shaft below said lowermost bearing and extending upwardly concentrically thereabout to enclose said shaft support and to prevent said solution from reaching said bearings; and said cup member being affixed to and rotating with said shaft.

3. In a flotation cell, means for supporting an impeller adjacent the bottom of said cell, comprising: a vertical shaft extending downwardly adjacent said shaft; means supporting said shaft at its upper extremity; bearings carried by said shaft support and supporting said shaft in said cell, the lower-most bearing being positioned 25 adjacent said impeller; a tubular cup member sealed to said shaft below said lower-most bearing and extending upwardly concentrically thereabout to enclose said shaft support and to prevent said solution from reaching said bearings; said cup member being affixed to and rotating with said shaft; and a stationary air sleeve surrounding said cup member; said air sleeve being open at its bottom to allow air to be drawn therethrough into said impeller.

4. On a flotation machine, an agitating chamber; a supporting member above said chamber; an impeller housing depressed into the bottom of said chamber; a bearing tube suspended from said supporting member over said housing; shaft bearings in said tube; a shaft extending downwardly through said bearings and terminating within said housing; an impeller carried by said shaft within said housing; and a tubular protecting member secured and sealed to said shaft below said bearing tube and extending upwardly about said bearing tube to a point above the solution line in said chamber.

5. On a flotation machine, an agitating chamber; a supporting member above said chamber; an impeller housing depressed into the bottom of said chamber; a bearing tube suspended from said supporting member over said housing; shaft bearings in said tube; a shaft extending downwardly through said bearings and terminating

within said housing; an impeller carried by said shaft within said housing; a tubular protecting member secured and sealed to said shaft below said bearing tube and extending upwardly about said bearing tube to a point above the solution line in said chamber; and an air jacket extending downwardly about said tubular protecting member and opening to said impeller below said protecting member.

6. On a flotation machine, an agitating chamber; a supporting member above said chamber; an impeller housing depressed into the bottom of said chamber; a bearing tube suspended from said supporting member over said housing; shaft bearings in said tube; a shaft extending downwardly through said bearings and terminating within said housing; an impeller carried by said shaft within said housing; a tubular protecting member secured and sealed to said shaft below said bearing tube and extending upwardly about said bearing tube to a point above the solution line in said chamber; and an air jacket extending downwardly about said tubular protecting member; said jacket being reduced in diameter at its bottom and extending within said impeller housing to define an annular outlet for the latter.

7. An impeller for flotation machines comprising: an annular rim band open at both its top and bottom; a cup-shaped member concentric within said rim band and forming a hub therefor; radical, axially extending vanes supporting said rim band from said cup-shaped member, said latter member being perforated to allow air to pass from said cup-shaped member into the spaces between said vanes; and means for securing a drive shaft at the middle of the bottom of said cup-shaped member.

8. An impeller for flotation machines comprising: an annular rim band open at both its top and bottom; a cup-shaped member concentric within said rim band and forming a hub therefor; radical, axially extending vanes supporting said rim band from said cup-shaped member, said latter member being perforated to allow air to pass from said cup-shaped member into the spaces between said vanes; and means for securing a drive shaft at the middle of the bottom of said cup-shaped member, said rim band having a greater diameter at its top than at its bottom; a similarly shaped impeller housing surrounding said rim band in close proximity thereto, said housing being completely open at its top; a bottom in said housing; and a pulp conduit in said housing below said bottom, their being an axially positioned passage from said conduit through the bottom of said housing.

9. An impeller for flotation machines comprising: a conical-shaped annular rim band open at both its top and bottom; a cup-shaped member concentric with said rim band and forming a hub therefor; radial, axially extending vanes supporting said rim band from said cup-shaped member; means for securing a drive shaft at the center of the bottom of said cup-shaped member; a similarly shaped impeller housing surrounding said rim band in close proximity thereto; a bottom in said housing; and a pulp conduit in said housing below said bottom, there being an axially positioned passage from said conduit through the bottom of said housing, and perforations in the bottom of said cup-shaped hub member to allow air to pass from said cup-shaped member into the pulp conduit below.

ALVA H. GARRETT.
